GRINDING MACHINE FOR INJECTION NEEDLES

Hachiro Enya, Tokyo, Japan

Application June 23, 1939, Serial No. 280,879
In Japan November 26, 1938

4 Claims. (Cl. 51—98)

My invention relates to improvements in a grinding machine for injection needles, and its object is to provide a simple and effective machine for grinding injection needles facilitating repeated use thereof.

Another object of my invention is to provide a device for automatically lubricating the grindstones and for correcting the working surface of the grindstone smoothly.

10 Injection needles have usually been abandoned after use of several times as the point becomes dull and it is difficult to re-grind the point to the normal condition by simple and ordinary means.

In accordance with my invention a simple 15 grinding machine is produced for facilitating the re-grinding of an injection needle by very simple and easy operation quickly by any body to the required sharpened point and is characterized in that three sets of grindstones are mounted on 20 the same shaft and the needle holder is arranged opposite to the grindstones and its angular position can be changed in a vertical plane on a pivotal axis and also swunged horizontally to give a suitable twist to the needle axis.

25 My invention will be better understood from the following description when considered in connection with the accompanying drawings, and its scope will be pointed out in the appended claims.

In the accompanying drawings, Fig. 1 is an elevation of a grinding machine of injection needles embodying my invention; Fig. 2 is a side elevation partially in section; Fig. 3 is its plan view; Fig. 4 is an end view of a part of Fig. 1; Fig. 5 is an upward plan view of the needle holder and its operating member; Fig. 6 is its side view; Fig. 7 is a sectional view of the grindstones; Fig. 8 is an explanatory drawing of the grinding operation and Figs. 9—A and B are an elevation and a side view of a needle tip respectively in an enlarged scale.

40 Referring to the drawings, 1 represents a machine base; 2 designates the supporting frame; 3 represents a pillar to which a combined needle holder and operating stock is mounted. 4 represents a main grindstone; 5 and 6 are sub-grindstones which are mounted on a shaft 9 at a spaced relation by means of distance pieces 7 and 8. 10 represents a pulley secured to one end of the shaft 9 adapted to be driven by a transmission belt 13 from a driving pulley 12 mounted on the shaft 11. 14 is a handle though a motor may be used to drive the pulley 12.

45 15 represents a holder of an injection needle 16 and has a projected axis 17, by which the holder is supported on an operating stock 18 and

is clamped by a nut 20 through a spring 19 in such manner that the holder 15 may be turned on the supporting axis 17 for a certain angle. The operating stock 18 is provided with a handle 21 and is secured to the member 22 by means of a 5 screw 23 to be rotated about the axis 23 while the member 22 is pivoted at 24 to a vertical axis 25 put in the pillar 3. The member 22 has a rod 26 projected to one side which is extended between the projections or recesses 27 below the 10 needle holder 15. 28 are stops projecting downwardly from the operating stock 18 serving to limit the right and left ranges of turning of the stock 18 by engaging the rod 26.

A spindle 29 is loosely mounted across the supporting frames 2 and has secured thereto an arm 30 which is provided with a needle press 31 on one end. The needle press 31 consists of a piece of fiber or other suitable material put in the casing and secured thereto by means of a screw 32 adjustably. On the opposite end of the arm 30 is formed a grindstone dresser 33 having a small finishing grindstone 34 secured by a screw 35 therein and an oil reservoir 36 is formed on the dresser 33. 37 represents a strip of leather serving to feed oil. An operating rod 38 is fixed to the spindle 29 and a spring 40 is connected between the arm 39 and the post 41.

The attachment of grindstones 4, 5 and 6 is shown in Fig. 7, wherein 42 is a tube put on the shaft 9 and passing through the grindstones 4, 5 and 6 as well as distance pieces 7 and 8 which are clamped together by means of a nut 43 and secured to the shaft 9 by a set screw 44. 45 is a collar secured to the shaft 9 by means of a set 35 screw 46 serving to prevent the side play of the shaft.

The operation of the grinding machine of this invention is as follows: A needle 16 is inserted through a hole of the needle holder 15 and clamped by a set screw 42 after the needle point has been adjusted suitably corresponding to the length of needle. Then the needle tip is brought to touch on the surface of the main grindingstone 4 by the handle 21 and the pressing piece 31 is brought on the needle tip by shifting the arm 38 which is biased by the spring 40 with suitable pressure. Then the pulley 12 is turned by the handle 14 to drive the pulley 10 and the grindstones. In this manner the needle tip is ground somewhat concave as shown by a in Fig. 9—A which is most important for the injection needle. Next the needle pressing piece 31 is lifted by turning the handle 38 and the handle 21 is moved horizontally to swing the operating member 18 55

to one side around the pivot 23, then the needle holder 15 is turned slightly about its axis 17 by the engagement of the rod 26 and projections 27 and thus the tip of the needle 16 is brought to make contact on the side surface of the grindstones 5 or 6 at a slightly twisted condition as shown in Fig. 8. The movement of operating member 18 is limited by the stop 28 and the rod 26 so as not to be turned excessively and occupies a condition as shown in Fig. 8. At such condition the pulley 12 is turned to rotate the grindstones to finish one side edge *b* of the needle tip. Then the handle 21 is shifted to the opposite position and similar operation is repeated to 15 grind the other side edge *b'* of the needle tip. To grind both side edges of the needle tip at a certain angle is very important to improve the penetration of needle or cutting ability in order not to give pain to the patient.

20 During the above operations the dresser 34 is pressed on the main grindstone 4 by turning the handle 38, then the surface of grindstone 4 can be smoothly finished with oil fed on its surface from thin strip 37 of leather. Thus by shifting 25 the handle 38 the pressing arm 30 secured to the spindle 29 can be turned from the dressing operation to the needle press very easily.

With the attachment of grindstones as shown in Fig. 7, the grindstones 4, 5 and 6 can be taken 30 out by loosening the set screw 46 and pulling out the shaft 9 together with the pulley 10 without disassembling the machine frames. Since the grindstones are assembled together on a tube 9 independently the distances between the pairs 35 of grindstones 5 and 6 can be easily adjusted as desired by interchanging the distance pieces 7 and 8 by simply loosening the nut 43 so that the grindstones can be easily put on or disassembled and easily adjusted. If the distance pieces 40 are distinguished by different colours for different dimensions the distance pieces can be easily replaced corresponding to the different sizes of the needle 16.

I claim:

45 1. A grinding machine for injection needles, comprising grinding element consisting of a main grindstone and two associated grindstones arranged to the left and right of said main grindstone and spaced therefrom by definite distances, said grindstones being fixed to a shaft 50 rotatably mounted on the machine frame, a needle supporting and operating member mount-

ed on a pillar at a position opposite to the main grindstone, a needle holder carried by said member, said needle operating member being constructed and arranged to be swung forward and from the main grindstone and also to be turned 5 to the right and left to any angular position to thereby turn the needle holder by an amount corresponding to the turning of the operating member to thereby move the needle tip through a certain angle so as to bring the needle tip on 10 the side surface of one or the other of said associated grindstones, and a needle pressing member secured to an arm projecting from a spindle rotatably mounted on the machine frame and adapted to press the needle tip on the surface 15 of the main grindstone.

2. A grinding machine for injection needles, comprising a main and two associated grindstones adjustably assembled on a tube which is sleeved on and secured to a grindstone shaft 20 which is rotatably mounted on the machine frame, means for driving said grindstone shaft, a needle pressing piece mounted on one end of an arm secured to a spindle rotatably mounted on the machine frame and operable by a spring to 25 a biased position, a grindstone dresser attached to the opposite end of said arm, a device for feeding oil to the dresser, an operating member pivoted on a supporting pillar to swing toward and from the main grindstone, a needle holder 30 mounted on said operating member on a horizontal axis, and engaging means between said needle holder and said operating member to turn the needle holder to a right or left position when the operating member is swung to the right or left. 35

3. A machine for grinding injection needles, comprising three grindstones mounted on the same shaft and spaced along said shaft by definite distances, a supporting device mounted adjacent and opposite the central grindstone on horizontal and vertical pivots, whereby it may be moved both parallel and transversely to the central grindstone, and a needle holder carried by said supporting device and movable therewith to cause a needle carried thereby to be moved into 45 engagement with the central grindstone or with either of the other grindstones.

4. A machine according to claim 3, in which the needle holder is movably connected to the supporting device and is constantly urged toward 50 the supporting device by spring means.

HACHIRO ENYA.
